UNITED STATES PATENT OFFICE.

JAMES C. PARSHALL, OF LINCOLN, NEBRASKA.

HAIR-CURLING IRON.

Application filed February 10, 1925. Serial No. 8,198.

To all whom it may concern:

Be it known that I, JAMES C. PARSHALL, a citizen of the United States, residing at Lincoln, in the county of Lancaster and 5 State of Nebraska, have invented certain new and useful Improvements in a Hair-Curling Iron, of which the following is a specification.

This invention relates to an improved 10 hair curling iron and it has particular reference to a contrivance of this class which is especially adapted for curling hair in a manner to produce what is known as a Marcel wave.

One object is to provide a comparatively 15 simple and inexpensive structure of this class which is highly practical and such in construction that it will enable the user to produce a uniform wave to impart a decidedly attractive and symmetrical appearance to the hair.

An important advantage is derived from 20 the particular construction which is such as to enable an unskilled person to use the tool to great advantage in crimping her own hair.

A further object is to generally improve 25 upon device of this class by providing an expansible and contractible device which is capable of being constructed into a compact 30 device to provide a comparatively small package for shipping and storage.

The invention, of course, embodies other 35 structural features and advantages and these will become apparent from the following description and drawing.

In the accompanying drawing forming a 40 part of this application and in which like numerals are employed to designate like parts throughout the same:

Figure 1 is a top plan view of a hair curling iron constructed in accordance with the present invention.

Fig. 2 is a side elevation thereof.

Fig. 3 is a top plan view showing the several parts, constituting the device, contracted to indicate when in use.

Fig. 4 is a detail side elevation of one end of the device as seen in Fig. 3.

Briefly, the device comprises a pair of 50 duplicate outer crimpers disposed in spaced parallelism and an intermediate member interposed between the first named crimpers and connected thereto through the medium 55 of means to permit movement toward and from each other for expanding the device

as seen in Fig. 1 or contracting it as seen in Fig. 3.

One of the outer crimpers is designated by the reference character 1 and the remaining one by the reference character 2. The intermediate crimpler is designated by the reference character 3. Each of the outer crimpers comprises a rod 4 having a cylindrical outer end portion 5 and provided upon its opposite ends with a suitably shaped flat handle 6. Pivotally connected as at 7 to the intermediate portion of each rod is a substantially semi-circular shield 8 which is adapted to bear against the cylindrical outer end portion 5 as in the ordinary hair curler.

Inward of the pivot 7 is an upwardly angled extension 9, the two extensions being connected together through the medium of a slotted link 10 and rivets or the like 11. The construction of the intermediate member 3 is reversed. In this instance, the outer end portion of the rod 12 is channel shaped in cross section as indicated at 13 and a cylindrical presser bar 14 is seated therein, being pivotally connected thereto as at 15 and provided with an elongated extension 16 beyond the pivot point.

This extension is disposed beneath the 85 slotted link 10, but it is obvious that by pressing the fingers upon the link 10 and depressing the same, the extension 16 will also be forced outwardly and the portions 8 and 14 will be rocked upon their pivots to 90 move them away from the complementary portions 5 and 6 to permit insertion of the hair to be curled.

If desired, flat springs 17 may be arranged between the bars proper and the 95 pivotally mounted members for normally maintaining the latter tightly pressed against the cylindrical and channel shaped portions 5 and 13 respectively. It will be noted that the inner end portion of the intermediate bar 12 is connected to the outer bars through the medium of two pairs of links 18, the links, as better shown in Fig. 4, being pivotally connected to the under sides of the bars 4. It will also be observed 100 from Fig. 4 that the links are somewhat twisted and are inclined downwardly toward their inner ends.

With this arrangement it will be seen that when the outer crimpers 1 and 2 are 110 moved toward each other, they will act on the intermediate crimpler 3 through the

medium of the links to slide the same rearwardly and downwardly with respect thereto.

In practice the strands of the hair are bunched and the bunch is extended crosswise of the cylindrical portion 5 and the intermediate channel portion 13, the shields 8 and the cylindrical member 14 being swung to an upwardly inclined position as approximately indicated in dotted lines in Fig. 2 to facilitate the insertion. The last named parts are released and under the action of the springs are pressed tightly against the coacting surfaces, thus crimping the hair in the usual way. Of course, prior to inserting the hair, the parts are thoroughly heated in the customary manner.

Under the arrangement of parts specified, it will be seen that there will be two upwardly convexed crimps and intermediate downwardly bowed crimps. In order to obtain the desired marcel effect however, the outer crimpers 1 and 2 are moved to approach each other as indicated in Fig. 3. The intermediate crimpler 3 under the action of the links 18 is thus moved rearwardly as shown in this figure and at the same time is moved downwardly to the approximate relatively inclined position shown in side elevation in Fig. 4. In this way the intermediate downwardly bowed curl or crimp is moved somewhat out of alignment with the two outer crimps, thus producing the proper marcel effect.

It is thought that the foregoing description taken in connection with the accompanying drawings will enable persons skilled in the art to which the invention relates to obtain a clear understanding of the same and for this reason, a more lengthy description is thought unnecessary.

Although the preferred embodiment of the invention has been clearly shown and described, it is to be understood that minor changes coming within the field of invention 45 claimed may be resorted to if desired.

Having thus described my invention, what I claim as new is:—

1. In a hair curling iron of the class described, a pair of substantially duplicate spaced parallel hair crimping members, an intermediate crimping member arranged between said first named members, all of said members embodying relatively stationary and movable parts between which the hair is adapted to be clamped, the parts being pivotally connected together, and the movable parts being provided at their inner ends with extensions, said extensions being inclined away from the stationary parts, and a link extending crosswise of the connected with the extensions for permitting all of said extensions to be depressed simultaneously for opening said movable parts.

2. A hair waver of the class described 65 comprising a pair of substantially duplicate spaced parallel hair crimping members including relatively stationary and movable parts between which the hair is adapted to be clamped, an intermediate crimpler 70 arranged between said first named crimping members, and a plurality of pairs of links connected to the bottoms of said members and the intermediate crimpler, said links being twisted and directed outwardly and 75 downwardly from the crimpler, whereby to move said crimpler longitudinally and downwardly with respect to said members when the latter are moved toward each other.

In testimony whereof I affix my signature.

JAMES C. PARSHALL.
